UNITED STATES PATENT OFFICE.

ROBERT Y. BARROWS, OF RUTHERFORD, NEW JERSEY, ASSIGNOR OF ONE-HALF TO
GEORGE H. HARMAN, OF GLEN RIDGE, NEW JERSEY.

ORGAN-PIPE.

1,074,768.

Specification of Letters Patent.

Patented Oct. 7, 1913.

Application filed October 27, 1911. Serial No. 657,128.

To all whom it may concern:

Be it known that I, ROBERT Y. BARROWS, a citizen of the United States, and a resident of Rutherford, State of New Jersey, 5 have invented an Improvement in Organ-Pipes, of which the following description, in connection with the accompanying drawings, is a specification, like letters on the drawings representing like parts.

10 In Letters Patent No. 1,006,425, dated October 17, 1911, I have illustrated and described how, by permitting the air to issue from a portion only of the slit in an organ pipe, I can change the power and tone-quality of the pipe without causing it to speak out of tune.

15 The present invention embodies a practical application of my earlier one, and shows how the latter may be applied to an existing set of organ pipes without difficulty or inconvenience. Moreover, the improvements are also concerned with the application of the invention to new pipes.

20 In my earlier patent, the slit through which the air issues to cause the pipe to speak, was shown as being divided up into one or more sections so as to provide a shortened slit or slits and controlling means were also shown whereby the air might be made 25 to issue through one or more of these slits to produce a different tone quality from that of the original pipe, although of the same pitch. In accordance with the present improvements, an additional slit is provided 30 for the same purpose and it has the advantage of leaving the original slit unchanged and of being made narrower than the original slit to reduce the thickness of the sheet of air issuing therefrom, all of which will 35 be understood upon reference to the particular description of the same which follows.

40 In the drawings which illustrate the invention as applied to wooden pipes, Figure 1 is a view in central vertical section of a wooden pipe having the invention applied thereto, and Figs. 2 and 3 are respectively a view in front elevation and a view in section as indicated by the line 3—3 in Fig. 1.

45 On reference to the drawings, it will be seen that the portion of the pipe right in front of the block *a* and just beneath the lip *d* is provided with a wind passage *b* and slit *b*¹, whereas in the ordinary wooden organ pipe it will be recalled that this portion of the pipe is simply a solid piece of

50 wood, usually referred to as the "cap," and forms with the front edge of the block *a* the usual slit *c*¹ from which the wind is discharged across the mouth of the pipe from the space *c* underneath the block. In the present case, the old plain cap has simply 55 been removed and a new cap substituted having the air passage and slit, as aforesaid. In constructing this cap, a plain piece of wood like the old cap may be cut at the top to receive an adjustable piece *m* and bored from the bottom for the air passage *b*, the latter being broadened out at the top to supply the whole length of the slit which is determined by the width of the piece *m*. For 60 convenience in cutting the air passage and forming the slit, it is preferable to cut said passage clear through to the rear of the cap and then glue a relatively thin piece *n* to the rear of the cap. The piece *n*, as can 65 readily be seen from the drawing, forms two slits, one with the block *a*, which is the usual slit of the pipe and extends substantially the full width thereof, and the other with the adjustable piece *m* which extends only 70 part way across the pipe. The length of the slit *b*¹ may be chosen to produce the particular power and tone quality of the pipe 75 desired. Moreover, the width of the slit *b*¹ may be adjusted through the piece *m* in 80 order to provide the precise narrowness of slit required to reduce the quantity of the air delivered by the desired amount. Of course, the slit *b*¹ may be cut in the cap 85 itself without providing any adjustable piece *m*, the latter simply serving as a convenient means of constructing and adjusting the slit. Where said piece *m* is employed and has been adjusted in the desired position, it will generally be permanently secured to the cap in some suitable manner as, 90 for instance, by gluing.

95 It will be understood, from a reading of my prior Letters Patent referred to above, that the two slits receive their wind supply 100 independently and that means are provided to cut off the wind supply of either at will. For instance, in the present case, the space *c* underneath the block communicates with the wind chest *o* through its foot *g*, while the 105 passage *b* communicates with the wind chest through a second foot *f* or some other suitable means; and sliders or stops *h* and *i* are provided to control each a complete set of feet, that is, one slider for all the feet *g*, 110

and one for all the feet *f*. It will be understood, of course, that the sliders *h* and *i* are independently connected with stop-handles at the keyboard or console, in the usual manner. Thus it will be seen that by closing the slider *i* and opening the slider *h*, all the pipes in the stop will speak their normal tone, while by opening the slider *i* and closing the slider *h*, their tone will be changed in quality, and reduced in power. And these changes are produced with absolutely no change in pitch. The slit *b*¹ will generally be adjusted and then fixed, in the first instance, to determine the thickness of the sheet of air delivered therethrough; in addition to this primary adjustment, it is desirable to provide some means for regulating the capacity of the air passage *b* which connects the source of wind supply with the slit *b*¹. Such regulating means may consist, for instance, of a plug, as *b*², provided in each cap and extending into the air passage *b*. Being accessible from the outside, these plugs may easily be moved so as to restrict more or less the corresponding passages. It is obvious that this regulating of the capacities of the air passages may be effected by any of the methods in common use and well known to organ builders.

30 It will be understood that other constructions of cap may be provided to embody a slit and an air passage, and be substituted for the old plain caps in organ pipes, and also that two or more of these additional slits may be provided in the cap to produce the result described in my aforesaid Letters Patent; and further that any of said additional slits may be sub-divided to control say one-third or two-thirds or some other fraction of the slit as shown with respect to the original slit in my aforesaid Letters Patent; but all such caps are considered to be within the scope of the present invention. These caps make it possible easily to apply the present invention, as well as that set forth in my prior Letters Patent aforesaid, to existing wooden pipes; for the only change required is to substitute the new caps for the old ones and connect their air passages with the wind chest. Finally, it is understood, of course, that the invention is not limited to application in wooden organ pipes.

50 I claim as my invention:

55 1. An organ pipe having a mouth, and

provided with a slit to deliver a sheet of air across said mouth and a second slit parallel to the first slit and also adapted to deliver a sheet of air across said mouth, in combination with a wind-chest, and means 60 to deliver air from the wind-chest through each of said slits independently.

2. An organ pipe having a mouth, and provided with two slits operatively related to said mouth so as to deliver two parallel 65 sheets of air across said mouth, in combination with a wind-chest, independent passages to deliver air from the wind-chest to the respective slits, and means to control the delivery of air through each passage independently of that through the other passage.

3. The combination with a wind-chest, an organ pipe, two hollow feet forming 75 passages from the wind-chest to the pipe, and a slider for opening and closing the passage 75 in each foot, said pipe having a mouth and being provided with two parallel slits of different length in which said passages terminate respectively, and each of said slits being adapted to deliver a sheet of air across said 80 mouth to cause the pipe to speak.

4. The combination of a wind-chest, an organ pipe, and means for delivering air from the chest to the pipe, said pipe having a lip, a cap and a block, the lip and cap forming a mouth for the pipe and the cap and block forming the normal slit of the pipe, the top edge of the cap being provided with a second slit and both of said slits communicating with the aforesaid means for 90 delivering air from the chest to the pipe, and means to control the delivery of said air through one slit independently of that through the other slit.

5. An organ pipe having a mouth, and 95 provided with a slit to deliver a sheet of air across said mouth and a second slit parallel to the first slit but of a different length and also adapted to deliver a sheet of air across said mouth, in combination with a wind- 100 chest, and means to deliver air from the wind-chest through one slit independently of that through the other slit.

In testimony whereof, I have signed my name to this specification, in the presence of 105 two subscribing witnesses.

ROBERT Y. BARROWS.
